UNITED STATES PATENT OFFICE.

EDGAR BOURQUIN, OF WALTHAM, MASSACHUSETTS.

LETTERING PEN.

Application filed December 31, 1924. Serial No. 759,186.

To all whom it may concern:

Be it known that I, EDGAR BOURQUIN, a citizen of the United States, and resident of Waltham, county of Middlesex, State of Massachusetts, have invented an Improvement in Lettering Pens, of which the following description, in connection with the accompanying drawing, is a specification, like characters on the drawing representing like parts.

This invention relates to lettering or ruling pens and it has for one of its objects to provide a novel pen of this type which can be used in the ordinary standard pen holder.

Another object of the invention is to provide an improved lettering pen which is constructed so that the ink will always flow freely and there will be no tendency for it to clog.

Other objects of the invention are to improve lettering pens in various ways all as will be more fully hereinafter set forth.

In order to give an understanding of the invention I have illustrated in the drawings a selected embodiment thereof which will now be described after which the novel features will be pointed out in the appended claims.

In the drawings:

Figs. 1 to 8 are sectional views of lettering pens embodying my invention;

Fig. 9 is a section on the line 9—9, Fig. 10;

Fig. 10 is a side view of a lettering pen embodying my invention showing it carried by the ordinary standard pen holder.

The pen herein illustrated is specially designed as a lettering, drawing or ruling pen and will be found useful by draftsmen, architects, engineers, etc. in connection with their work.

The pen has a tubular body provided with an ink-receiving reservoir and a tubular nozzle through which the ink is delivered.

Referring to Fig. 10 the pen is indicated generally at 1, it having a tubular body which terminates at its lower end in the nozzle 2. The pen is supported by a clamping member 3 which is formed with two jaws 4 that embrace the tubular body of the pen, said jaws being shown as formed by bending a strip of sheet metal into the U shape shown in Fig. 9.

The portion 6 of this holder is received between the arms 7 of the forked portion of a shank member 8, the latter having the parti-cylindrical portion 9 that has substan-

tially the same shape as the stem or shank of a steel pen and is adapted to be inserted into the groove in the ordinary standard pen holder 10 in place of an ordinary steel pen.

The intermediate member 5 is pivotally connected to the forked portion 7 of the shank so that the pen 1 may have different angular positions relative to the pen holder 10. This pivotal connection is provided for by means of a combined pivotal and clamping screw 11 which extends through the arms 7 of the fork and through the portion 6 of the clamping member, said screw having a thumb nut 12 screw-threaded thereon.

This screw 11 performs three different functions. It acts as a clamping screw for clamping the arms 4 and 5 of the clamping member tightly about the pen, it also acts as a pivotal support between the clamping member and the shank so as to permit the pen to be swung into different angular positions, and it acts further as a clamping screw for clamping the clamping member in its adjusted position.

Lettering pens embodying this invention usually come in sets, each set having therein pens adapted to draw lines of different widths. The construction herein provided has the further advantage that the pens are readily interchangeable for by loosening the clamping nut 12 a pen can be readily removed from the clamping jaws and another pen inserted in its place.

The pens may be made in various ways. In Fig. 1 I have shown a simple form of pen which comprises simply a cylindrical body 13 having the ink-receiving reservoir 14 therein, the lower end of the body being tapered to form the nozzle 2 which has the ink duct 3 extending therethrough.

The pen shown in Fig. 2 differs from that shown in Fig. 1 in the construction of the nozzle. In Fig. 2 the nozzle 15 of the pen is made in a separate piece which has a sort of funnel shape and is secured or made fast to the body in any suitable way as by soldering. This form is specially applicable for a pen adapted for fine lettering and which has a very small duct 3.

The pen shown in Fig. 3 has a cylindrical body portion 13 and ink reservoir 14 and the nozzle 16 thereof is provided with a slit 17.

In Fig. 5 a similar construction is shown except that the slit is very nearly closed up, this type of pen being specially applicable for some kinds of work.

In Fig. 6 the nozzle 18 is flared outwardly at its lower end as shown at 19 and it is also provided with a slit 17. This type of pen is especially applicable for making wide lines.

In Figs. 7 and 8 I have illustrated a form of pen which employs an agitator or clearer that operates automatically to keep the pen from becoming clogged and to ensure an even flow of ink. In this embodiment the 10 body of the pen is shaped to present the portion 20 of larger diameter and the intermediate portion 21 of smaller diameter between the portion 20 and the nozzle 22.

Situated within the pen is a cleaning device which is provided with a grooved body portion 23 that is located within and guided by the portion 21 of the pen and which is also provided with a cleaning pin 24 that extends down through the nozzle. The 20 cleaning point is of such a length that when the fluted or grooved body 23 rests on the bottom of the portion 21 of the pen the point of the cleaner will project slightly through the end of the nozzle. Enlarged portion 20 of the body, together with the portion 21, provides an ink reservoir of relatively large capacity.

The cleaning device is provided with a stem 25 by which it may be manipulated manually whenever it is desirable to clean the pen. When this pen is used the tip of the nozzle is placed against the paper and the engagement of the paper with the end of the cleaning pin 24 will force the cleaning device upwardly and separate it slightly from the seat 26 on which it normally rests. During the writing operation, therefore, the cleaner is supported by the paper and is free for a slight vertical movement. The movement 40 of the cleaner due to placing the tip against the paper or removing it from the paper during the latter operation results in preventing the pen from clogging and keeping it in a free flowing condition.

In Fig. 8 I have illustrated a different embodiment of my invention which is specially applicable for a pen having a very wide-mouthed nozzle. In this construction the pen has a cylindrical body 27 and the 50 end of the nozzle is flared widely as shown at 28. The cleaner in this embodiment is formed with an enlarged portion 29 that normally seats against the seat 30 formed by the taper of the nozzle. The cleaner in 55 this instance is hollow and the lower end 31 is in the form of a tube which has such dimensions that when the enlarged portion 29 rests against the seat 30 the end of the cleaner will project slightly below the nozzle. The cleaner is also provided with a 60 stem 25 by which it may be manually manipulated.

The device shown in Fig. 8 operates in the same way as that shown in Fig. 7 so far as keeping the pen clean is concerned.

It will thus be seen that my invention provides an interchangeable lettering pen which is adapted to be mounted in the ordinary standard pen holder and which, therefore, does not require any particular type 70 of pen holder. It will also be seen that the invention as illustrated in Figs. 7 and 8 shows a self-cleaning pen.

While I have illustrated herein a selected embodiment of my invention I do not wish to be limited to the constructional features shown.

I claim:

1. In a lettering pen, the combination with a pen having a tubular body and a delivery nozzle, of a clamping member in which the pen is removably clamped, and a shank supporting the clamping member and constructed to be inserted in an ordinary standard pen holder.

2. A lettering pen such as described in claim 1 in which the clamping member is pivoted to the shank so that the pen can be adjusted into different angular positions relative to the pen holder.

3. In a lettering pen, the combination with a tubular pen member, of a U-shaped clamping member having clamping jaws embracing said pen member, a supporting shank having a forked portion to receive the clamping member, said shank having a curved portion adapted to fit the pen-receiving groove of an ordinary standard pen holder.

4. In a lettering pen, the combination with a tubular pen member, of a U-shaped clamping member having clamping jaws embracing said pen member, a supporting shank having a forked portion to receive the clamping member, said shank having a curved portion adapted to fit the pen-receiving groove of an ordinary standard pen holder, and a combined pivotal and clamping screw extending through the clamping member and the forked portion of the stem 105 and adjustably clamping them together.

5. In a lettering pen, the combination with a tubular body having an ink reservoir and a nozzle, of a cleaning device in the ink reservoir, said cleaning device having a pin portion extending through the nozzle and normally projecting slightly below the latter whereby when the pen is used the cleaning device will be raised slightly by contact with the paper.

In testimony whereof, I have signed my name to this specification.

EDGAR BOURQUIN.
